UNITED STATES PATENT OFFICE.

EZRA S. BABCOCK, OF WALWORTH, ASSIGNOR OF ONE-HALF TO PAUL M. GREEN, OF MILTON, WISCONSIN.

COMPOUND METAL-WORKING MACHINE.

SPECIFICATION forming part of Letters Patent No. 434,231, dated August 12, 1890.

Application filed February 13, 1890. Serial No. 340,282. (No model.)

To all whom it may concern:

Be it known that I, EZRA STILLMAN BABCOCK, of Walworth, in the county of Walworth, and in the State of Wisconsin, have invented certain new and useful Improvements in Compound Metal-Working Machines; and I do hereby declare that the following is a full, clear, and exact description thereof.

My invention relates to compound metal-
10 working machines; and it consists in certain
peculiarities of construction, as will be fully
set forth hereinafter and subsequently
claimed.

In the drawings, Figure 1 is a side elevation
15 of my improved machine, partly broken
away to better illustrate the construction.
Fig. 2 is a vertical transverse section on the
line 2 2 of Fig. 1. Fig. 3 is a like section on
the line 3 3 of Fig. 1, showing also a broken
20 portion of the punch-supporting shell. Fig.
4 is a transverse section on the line 4 4 of Fig.
5. Fig. 5 is a horizontal section on the line
5 5 of Fig. 1, and Fig. 6 is a like section on
the line 6 6 of Fig. 1.

25 My present invention is, in part, an improvement on the device patented to me February 14, 1888, and numbered 377,976, and, like that, combines a vise with a punching and shearing machine, but differs from said
30 machine in details of construction, as hereinafter pointed out.

35 A is the stationary standard of my machine, having a flange *a*, by which it may be suspended from a bench when used in a vertical position, and above this flange is the head *B*, containing one jaw of the vise, the upper part of said head terminating in a vertical face *e*.

40 C is the swinging standard, having a head *D*, both heads *B* and *D* being longitudinally slotted or cut out centrally, as shown at *g h*, but the head *D* being open at the top and only rising to the height of the cut-out portion or slot of the head *B*. As in my prior
45 patent hereinbefore named, the swinging standard *C* is pivoted at *b* between a pair of bearing-straps *E E*, which are themselves secured to the stationary standard *A* between the lugs *d d* by a bolt *c*. The side walls
50 of the two heads *B D* have opposing V-

shaped concave faces *f f*, and fitted in the slots *g h* is a sliding head *F*, which has a V-shaped concave serrated face *i*, the said head *F* having a longitudinal screw-threaded bore *f'* for the reception of one end of a screw *G*. 55 In my prior patent just named the screw was movable longitudinally and its forward end was secured to the rear end of the sliding head; but in my present device the screw *G* is formed with a solid collar *k'*, fitting in a 60 seat in the end wall of the head *D*, the outer end of the screw from this point and the bore in the said end wall through which it passes being smooth, and there being another collar *k* secured to said smooth end just outside 65 said end wall, so that as now constructed, when said screw *G* is turned by its bar *j* or other hand device, the sliding head *F* screws upon or from the screw (according to which way the latter is being revolved) instead of 70 moving with the said screw longitudinally, as heretofore. Further, in my present device the sliding head *F* is provided with laterally-projecting base-flanges *n' n'* on each side, which engage with longitudinal grooves *o' o'* 75 at the base of the side walls of the slot *h* in the head *D*, to prevent said sliding head *F* from rising from place when it is wholly within the open-topped slot *h* in the said head *D*, and the other vertical-faced jaw *e'* of the 80 vise is formed solidly with said head *F* in my present device, the transverse ends of said vise-jaw *e'* resting on top of the side walls of the head *D* and projecting beyond them, all as best shown in Fig. 2. 85

The base of my machine is formed, as before, with two parallel horizontal arms *I* and *J*, the former extending from the standard *A* and rigidly united at that end by a piece *H*, having projecting ears *k k*, said piece and 90 ears being flush with the outer edge of the stationary standard *A*, so that the device may be placed horizontally of its greatest length on a bench when more convenient to operate it in this position than in the vertical position shown in Fig. 1. The swinging standard *C* projects below the bottom line of the arms *I* and *J*, and is bifurcated to receive one end of a link *K*, pivoted at *m'* to said standard, the other end of said link being pivoted at *m* 95 100

to the similarly-bifurcated eccentric-head *n* of a lever *L*, which head is in turn pivoted at *p* between the arms *I* and *J*.

M is a bell-crank-shaped detent journaled 5 on a shaft or pin *q*, which extends through the said arms *I* and *J* adjacent to the piece *H*, and when my machine is to be used as a vise the detent *M* is turned, as shown in Figs. 1 and 6, with the end of the long arm of said 10 bell-crank pressing against the adjacent edge of the swinging standard *C*; but when the machine is to be used for punching or shearing, then the lower or short arm of the detent is moved and the long arm thrown up and 15 back against the piece *H*, out of the way of the swinging standard.

The punching device in my present machine is constructed as follows: The upper part of the stationary standard *A*, just below its head 20 *B*, is grooved out for the reception of a circular plate *N*, provided near its circumference with a series of holes *t t t t* of different diameters, and below this groove there is secured by screw-bolt *u* the lower flange *r* of a supporting-shell *O*, the upper portion of which is offset, as shown in Figs. 1 and 5, so as to furnish space between its inner surface and that of the standard *A* for the metal to be punched, said upper portion having two rearward-extending wings *s s*, having horizontal grooves *s' s'* in their upper inner rear surfaces, while the front or inner wall of said shell *O* is provided with a hole *v* therethrough for the admission of the punch *P*, which latter is secured by a set-screw *w* in the stock *Q*, which in turn is pivoted by a bolt *x* to the standard *C*, the end of said stock *Q* being rounded and fitting within a corresponding recess *x'* formed in said standard, which latter is 25 further cut out or recessed, as shown at *x''*, for the reception of the described upper portion of the shell *O*, the rear wings *s s* of which project over and rest upon the top edges of the described bearing-straps *E E*, as best 30 shown in Fig. 4. It is designed to use a series of these punches *P* corresponding to the diameters of the holes *t t* in the circular plate *N*, which plate is turned around within its groove to bring the hole *t* of desired diameter 35 opposite the hole *v* in the shell *O* for use in connection with the particular punch *P* to be used at any time; and for the purpose of steadyng the stock *Q* and insuring that the punch *P* shall always be properly guided to place, the said stock *Q* is provided with trunnions *s'' s''*, that fit and move in the described 40 grooves *s' s'* in the rear side wings *s s* of the supporting-shell *O*.

R R represent the shearing-blades of my 45 machine, which are secured by bolts *y y* with in suitable recesses *z z* formed in the standards *A* and *C*, as shown in Fig. 1, the blades in this present case differing from those in my aforesigned prior patent, in that, whereas they were formerly set with practically vertical cutting-edges, (in the position of the machine shown in Fig. 1,) they are now formed

with inclined opposing cutting-edges nearest together at the top and with the space normally between them increasing regularly from top 70 to bottom, which gives a better cut than the former arrangement. As in my said prior patent, all of the parts are operated by the lever *L*, which brings the swinging standard *C* and its attachments against the stationary 75 standard *A*, so that the metal being worked can be held in the vise or punched or sheared, as desired, by a single movement of the said lever, while the present construction of the vise enables the upper vertical-faced jaw, 80 which is connected to the swinging standard, to be adjusted, which is a great improvement over the former construction, and at the same time the concave faces of the vise can also be adjusted, and the present construction of the 85 punching device insures better results with greater convenience than formerly.

Having thus fully described my invention, what I claim as new, and desire to secure by Letters Patent, is—

1. In a compound metal-working machine, the combination of a stationary standard having a fixed vertical-faced vise-jaw at its upper end, and a swinging standard pivotally connected to the stationary standard and 95 having a vertical-faced vise-jaw at its upper end independently movable relative to its movable supporting-standard, with an operating-lever having an eccentric-head pivoted to the base-frame of the machine and united 100 by a link to the lower end of the said swinging standard, substantially as set forth.

2. In a compound metal-working machine, the combination of a stationary standard having stationary vertical-faced and concave-faced vise-jaws at its upper end and a swinging standard pivotally connected to the stationary standard and having vertical-faced and concave-faced vise-jaws at its upper end movable independently of their movable supporting-standard, with an operating-lever having an eccentric-head pivoted to the base-frame of the machine and linked to the lower end of the swinging standard, substantially as set forth.

3. In a compound metal-working machine, the combination of a stationary standard, a swinging standard pivoted thereto, and an operating-lever having an eccentric-head pivoted to the base-frame of the machine and 120 linked to the lower part of the said swinging standard, with a pair of shearing-blades secured to the said standards and having inclined opposing cutting-edges nearest together at the top and with the space normally 125 between them increasing regularly from top to bottom, substantially as set forth.

4. In a compound metal-working machine, the combination of a stationary standard and a swinging standard pivoted thereto, each 130 standard having vertical-faced and concave-faced vise-jaws at its upper end, and an operating-lever pivoted to the base-frame of the machine and linked to the swinging stand-

ard, with a bell-crank-shaped detent having arms of unequal length pivotally secured to said base-frame adjacent to the stationary standard for engagement with the said swinging standard, substantially as set forth.

5. In a compound metal-working machine, the combination of a stationary standard provided with a groove on its inner face, a circular plate provided with a series of perforations adjacent to its circumference and of different diameters, and a supporting-shell secured to said standard below said groove and having a perforated offset upper portion with two rearward-extending wings provided 15 with horizontal grooves in their upper inner rear surfaces, with a swinging standard pivotally connected to said stationary standard and recessed for the reception of the upper portion of said supporting-shell, a punch- 20 stock pivotally connected to said swinging standard and fitting between the said rear wings of said supporting-shell, and having trunnions fitting in the said grooves in the 25 said wings and adapted for the reception of a punch, and an operating-lever pivoted to the base-frame of the machine and linked to the said swinging standard, substantially as set forth.

6. In a compound metal-working machine, 30 the combination of a stationary standard hav-

ing a head centrally grooved and provided with stationary concave-faced vise-jaws and an upper stationary vertical-faced vise-jaw, a swinging standard pivotally connected to said stationary standard, and having a head also 35 centrally grooved but open at the top and only rising to the height of the groove in the head of the other standard, and having stationary concaved vise-jaws, a sliding head within said groove having a concave-faced 40 vise-jaw, and above the same a transverse extension solid therewith resting on the side walls of the head of the swinging standard and having a vertical-faced vise-jaw and a longitudinal screw-threaded bore, a screw 45 passed through the end wall of the said head of the swinging standard and engaging with the said bore, and an operating-lever pivoted to the base-frame of the machine and linked to the said swinging standard, substantially 50 as set forth.

In testimony that I claim the foregoing I have hereunto set my hand, at Walworth, in the county of Walworth and State of Wisconsin, in the presence of two witnesses.

EZRA S. BABCOCK.
